(57) **CLAIM**

The ornamental design for a lift truck, as shown and described.

DESCRIPTION

FIG. 1 is a front elevation view of the lift truck, showing my new design;

FIG. 2 is a back elevation view of the design as shown in FIG. 1;

FIG. 3 is a left side view of the design as shown in FIG. 1;

FIG. 4 is a right side view of the design as shown in FIG. 1;

FIG. 5 is a top plan view of the design as shown in FIG. 1;

FIG. 6 is a bottom plan view of the design as shown in FIG. 1; and,

FIG. 7 is a perspective view of the design as shown in FIG. 1.

The broken lines shown in the figures are for the purpose of illustrating portions of the lift truck and form no part of the claimed design.
